No. 659,045.

Patented Oct. 2, 1900.

A. AMESS.
PERMUTATION PADLOCK.

(Application filed Feb. 26, 1900.)

(No Model.)

UNITED STATES PATENT OFFICE.

AGNESS AMESS, OF MINNEAPOLIS, MINNESOTA.

PERMUTATION-PADLOCK.

SPECIFICATION forming part of Letters Patent No. 659,045, dated October 2, 1900.

Application filed February 26, 1900. Serial No. 6,444. (No model.)

To all whom it may concern:

Be it known that I, AGNESS AMESS, of the city of Minneapolis, county of Hennepin, State of Minnesota, have invented certain new and useful Improvements in Permutation - Padlocks, of which the following is a specification.

The invention relates to permutation-locks; and one object of the invention is to provide improvements in the construction of the lock shown and described in Letters Patent of the United States No. 643,448, granted to me February 13, 1900.

A further object is to adapt the lock shown in said patent for use as a bicycle-lock.

15 The invention consists generally in various constructions and combinations, all as hereinafter described, and particularly pointed out in the claims.

In the accompanying drawings, forming 20 part of this specification, Figure 1 is a plan view of my improved bicycle-lock. Fig. 2 is a longitudinal section of the same. Fig. 3 is a similar view with the locking devices removed. Fig. 4 is a sectional view showing 25 the lock closed. Fig. 5 is a view of one of the locking members. Fig. 6 is a sectional view on the line *a a* of Fig. 3. Fig. 7 is a similar view on the line *b b* of Fig. 2. Fig. 8 is a sectional view on the line *c c* of Fig. 2. 30 Fig. 9 is a sectional view on the line *d d* of Fig. 2. Fig. 10 is a sectional view on the line *e e* of Fig. 4. Figs. 11 and 12 are views of the tumblers. Figs. 13 and 14 are views of the spring provided within the tumblers. 35 Figs. 15 and 16 are sectional views of the tumblers, showing the springs therein. Fig. 17 is a view of one of the sectional washers. Figs. 18 and 19 are views showing a modification of the sectional washer opened and 40 closed. Figs. 20 and 21 are views of a spring-washer for locking the sectional washer in position. Fig. 22 is a view of the frictional washer.

In the drawings, 2 represents a curved arm 45 or member having a stud 3 at one end and at the other end a head 4, wherein a recess 5 is provided to receive the exposed end of the lock mechanism, as hereinafter described. Formed integrally with the head 4 is a hollow 50 spline 6, having a longitudinal slot 7, wherein in a locking-bar 8 is arranged, having a series of teeth 9 projecting through said slot. The

outer end of said bar is provided with an inclined slot 10, through which passes a pin 11, securing said bar within the hollow spline. 55 The inner end of said bar extends into a recess 12 in said head, and a spring 13 is provided beneath said bar and normally holds the same in a raised position with its teeth projecting through said slot, its inner end in 60 engagement with the wall at the top of the recess 12 and the pin 11 at the bottom of the slot 10. A sufficient space is provided beneath said bar to permit it to be depressed when the members of the lock are forced 65 together; but when the lock is closed the inclination of the slot 10 with respect to the teeth of the bar will produce a wedging effect should any one attempt to pull the lock open and serve to draw the teeth of the bar and the 70 locking-washers closer together. I prefer to provide a locking-bar having three teeth corresponding to the number of tumblers provided on the lock; but it will be understood that a greater or less number of teeth and tumblers may be provided, if preferred. The other 75 member of the lock comprises an arm 14, having a socket 15 to receive the stud 3, and a head 16, provided on its periphery with a series of letters or characters corresponding to the 80 characters provided on the periphery of the tumblers and forming the first letter of the word that composes the combination of the lock. A hollow shaft or spindle 17 is formed integrally with said head and is adapted to 85 receive the spline 6 and is provided with a longitudinal slot 18, wherein the locking-bar 8 is slidable.

19 represents a series of rotating tumblers provided on the spindle 17 and having 90 flanged peripheries 19', provided with a series of characters which when the tumblers are rotated may be aligned with any one of the characters on the periphery of the head 16, permitting the operator to form any desired 95 combination of letters or characters, substantially as described in my patent referred to. The spindle 17 is provided with a series of annular grooves 20 to receive sectional washers arranged between the tumblers. 100 These washers comprise a section 21, semicircular in form, having notches 22 in its end to receive the ends of a segment 23, fitting therein and completing the circle. The segment

23 is provided with a slot 24, and the section 21 has a pin 25 opposite the slot 24 and adapted to fit into one of a series of depressions 26, provided on one face of the tumblers 19. 5 Each of these depressions is opposite a character on the periphery of the tumbler, and when the tumblers have been set to the proper combinations to permit the lock to be opened the slots 24 will register with the longitudinal slot in the spindle, permitting the locking-bar to be drawn out; but upon turning the tumblers in either direction the notches 24 will be moved away from the slot in the spindle and the bar locked therein. 10 The sectional washers are concealed and protected from injury within recesses provided in frictional washers 19", arranged on said spindle between the tumblers. The frictional washers are provided with lugs 19", adapted to fit 15 into a longitudinal groove 27, provided in said spindle, and whereby said washers are locked against rotation.

In adapting this form of lock for use as a bicycle-lock it is desirable to provide some 20 means whereby the operator can ascertain the position of the tumblers in the dark. I therefore prefer to provide a zero or starting point for all the tumblers and in connection with each tumbler employ a click device, 25 each click produced by rotating the tumbler, indicating to the operator that the tumbler has advanced one letter or character. If the operator knows the characters that are in alignment on the tumblers and head when 30 the tumblers are at their starting-point, by counting the clicks as each tumbler is rotated he can easily set the tumblers for any desired combination, even if it is too dark to see the characters. With this end in view I provide 35 a spring 28, in the form of a flat ring split on one side and having its ends spread apart and one provided with a lug 29, adapted to slide in said longitudinal groove to prevent the spring from turning with the tumblers. 40 The opposite end of the spring is provided with a rounded projection 30, that bears upon the annular series of projections 31, provided in the opposite face of each tumbler from the 45 depressions 26. One end of the spring being locked in the groove 27, it will be obvious that as each tumbler is turned the opposite end of the spring will slide over the lugs 31 and produce a clicking sound as the tumbler is rotated. To form a starting-point for the tumblers and permit the operator to ascertain 50 their position in the dark, I prefer to cut away one or more of the lugs 31, as indicated in Fig. 11, so that as the end of the spring slides over the lugs and reaches the point 55 where one or more of them have been cut away the spring will drop into the space indicated in Fig. 16 and striking the adjoining lug will prevent further rotation of the tumbler in that direction. Suppose, for instance, the lock should be made with the lug 60 cut away opposite the letter "X" on each of the tumblers. The operator, knowing this,

can easily set the tumblers in the dark back to the starting-point, and then counting the clicks from that point readily open the lock 70 set for any combination.

All the sectional washers are concealed and protected from injury by any one attempting to pick the lock by the frictional washers provided between the tumblers; but at the outer end of the hollow spindle, where no frictional washer is used, I prefer to provide another form of locking-washer, as shown in Figs. 18 and 19. This washer consists of two sections 75 32 and 33, hinged together at one end. At their opposite ends the sections are provided, respectively, with a lug 34 and a notch 35. When the sections are pressed together, the lug entering the notch will lock the ends of the section and prevent the washer from being accidentally disengaged from its groove. This washer has a pin and slot corresponding 80 to those provided in the washer illustrated in Fig. 17. To prevent the sectional washer from slipping off the end of the spindle, I 85 prefer to provide a spring-washer 36, split on one side and having lugs 37 on its ends. An annular groove 38 is provided in the end of the spindle adapted to receive said spring-washer, and the lugs 37, engaging the edges 90 of the longitudinal groove in said spindle, as shown in Fig. 1, prevent the washer from rotating with the tumbler. In Fig. 5 I have 95 shown a spindle wherein the spring-washer is dispensed with, a single groove being provided to receive the form of washer shown in Figs. 18 and 19.

To prevent the spline from being pulled out of the hollow spindle when the lock is opened, I prefer to provide a lug 39, formed by cutting away the under side of the spline, and in said hollow spindle I provide a transverse slot 40, adapted to receive the locking-plate 41, that is held in said slot by one of the frictional washers. As shown in Fig. 3, the plate 41 will engage the lug on the spline and prevent the members of the lock from being 100 pulled apart.

I consider the form of sectional washer shown in Fig. 17 preferable to the one employed between the tumblers in my patent referred to above, as the sections 21 and 23 fit snugly together and are less liable to drop out of place than when made in two equal parts, and consequently require less support 110 from the frictional washers. At the end of the spindle I prefer to use the washer shown in Figs. 18 and 19, as in this position the washer is not inclosed, as it is between the tumblers, and it is consequently desirable to 115 lock the ends of the sections together.

Having thus described my invention, I claim as new, and desire to secure by Letters Patent—

1. A permutation - lock, comprising two 120 members having heads provided with outwardly-extending interlocking arms, a spline having a longitudinal slot provided on the head of one member, a toothed locking-bar

provided in said slot and having an inclined slot, a pin passing through the slot in said bar and permitting a limited vertical and longitudinal movement thereof, a spring provided beneath said bar and normally holding the same in the upper part of the slot in said spline, a hollow spindle wherein said spline is slidable and having a longitudinal slot to receive said bar and provided with a series 5 of annular grooves, a series of rotating tumblers provided on said spindle, a corresponding series of washers provided in said annular grooves and controlled by the movement of said tumblers and adapted to engage the 10 teeth of said bar and thereby lock said members together, substantially as described.

2. The combination, in a permutation-lock, with a locking member having a hollow spindle, of a second member having a spline and 15 a locking-bar slidable in said spindle, said spindle having a series of annular grooves in its surface and provided also with a longitudinal slot to receive said bar, a sectional washer provided in each of said annular 20 grooves and comprising interlocked sections 21 and 23 having, respectively, a pin 25 and a slot 24, a series of tumblers corresponding in number to said washers provided on said spindle and having annular depressions to 25 receive said pins 25, whereby said washers are rotated with said tumblers, and said slots 24 being adapted to register with the longitudinal slot in said spindle as said washers and tumblers are rotated, substantially as described.

3. In a lock of the class described, the combination, with a member, having a hollow spindle provided with a longitudinal groove, of a series of rotating tumblers provided on 30 said spindle, each tumbler having an annular series of lugs in its surface, springs provided on said spindle having lugs to enter the longitudinal groove therein and be locked thereby against rotary movement and the 35 free ends of said springs being adapted to bear upon said lugs as said tumblers are rotated, substantially as described.

4. In a lock of the class described, the combination, with a member having a hollow spindle provided with a longitudinal groove, of a 40 series of rotary tumblers provided thereon, each tumbler being provided with an annular series of lugs or projections arranged at intervals on said tumblers, springs comprising 45 split rings having lugs to enter said longitudinal groove and bear at their opposite ends upon said lugs in said tumblers and adapted to slide over the same as said tumblers are rotated and one or more of said lugs on said 50 tumblers being cut away to permit the ends

of said springs to drop into the space between the preceding and succeeding lugs and thereby limit the rotation of said tumblers in one direction, substantially as described.

5. In a lock of the class described, the combination, with a member having a hollow spindle provided with a longitudinal groove, of a series of rotating tumblers provided thereon, each having an annular series of lugs or projections, a spring provided in each of said tumblers, each spring having a lug to enter said longitudinal groove and bear upon said lugs in said tumblers as they are rotated, and one or more of said lugs in said tumblers being cut away to permit the end of the spring to 75 drop into the space between the succeeding and preceding lugs and thereby lock said tumblers against rotation in one direction, substantially as described.

6. In a lock of the class described, the combination, with a member having a hollow spindle provided with a series of annular grooves and a longitudinal slot and a longitudinal groove, of a second member having a spline telescoping with said spindle and a toothed locking-bar slidable in said slot, a series of tumblers provided on said spindle, frictional washers provided between said tumblers and having lugs to enter said groove, sectional washers provided in said annular groove and 80 adapted to rotate with said tumblers and having slots adapted to register with said longitudinal slot, a washer provided at the end of said spindle and comprising two sections hinged together, on one side of said washer 85 and provided with an interlocking notch and lug upon the opposite side, whereby the sections are held firmly together, and a spring-washer provided on said spindle outside said 90 hinged washer, substantially as described.

7. In a lock of the class described, the combination, with a locking member, having a hollow spindle provided with a longitudinal slot and a series of annular grooves in its surface, of a series of rotating tumblers provided on said spindle, a washer adapted to rotate with said tumblers provided in the annular groove at the end of said spindle and comprising two sections 32 and 33 hinged together, said sections having, respectively, an interlocking lug and notch on the opposite side from said hinge, and a slot to register with said longitudinal slot, for the purpose specified.

In witness whereof I have hereunto set my hand this 21st day of February, 1900.

AGNESS AMESS.

In presence of—

RICHARD PAUL,
M. C. NOONAN.
